Primary Examiner—Ruth McInroy*Attorney, Agent, or Firm*—A. Burgess Lowe; Thomas R. Kingsbury**[57] CLAIM**

The ornamental design of a vacuum cleaner nozzle, as shown and described.

DESCRIPTION

FIG. 1 is a front elevational view of a vacuum cleaner nozzle showing my new design;

FIG. 2 is a top plan view thereof;

FIG. 3 is a right side elevational view thereof;

FIG. 4 is a left side elevational view thereof;

FIG. 5 is a rear elevational view thereof; and,

FIG. 6 is a bottom plan view thereof.

The details shown in broken lines in FIGS. 5 and 6 are shown for illustrative purposes only and form no part of the claimed design.
